UNITED STATES PATENT OFFICE.

BEATRICE E. LINDBERG, OF FARIBAULT, MINNESOTA.

SCHOOL-LOOM.

SPECIFICATION forming part of Letters Patent No. 764,479, dated July 5, 1904.

Application filed August 20, 1902. Serial No. 120,339. (No model.)

To all whom it may concern:

Be it known that I, BEATRICE E. LINDBERG, a citizen of the United States, and a resident of Faribault, in the county of Rice and State 5 of Minnesota, have invented a new and Improved School-Loom, of which the following is a full, clear, and exact description.

This invention relates to a device for teaching children the art of weaving and for enabling them to produce small woven articles.

The present improvement lies in an attachment which enables hammocks to be woven. The loom with the said attachment is particularly adapted to kindergarten purposes for 15 weaving dolls' hammocks; but it is obvious that it could be adapted to hammocks of a larger size, if so desired.

This specification is an exact description of one form of the invention, while the claims define the actual scope thereof.

Reference is to be had to the accompanying drawings, forming a part of this specification, in which similar characters of reference indicate corresponding parts in both views.

Figure 1 is a plan view of the invention, and Fig. 2 is a section on the line 2 2 of Fig. 1.

a indicates the side bars, and *b* the end bars, of the device. The end bars *b* are notched at the points indicated at *b'*, so that the warp-threads may be laid therein, as shown. *c* indicates the lay, which slides on the side rails *a* and has notches *c'* therein for the reception of the warp-threads. These elements are all the same as those disclosed in my prior patent on 35 a school-loom, dated July 1, 1902, No. 703,799.

The end rails *b* project up above the side rails *a*, as shown best in Fig. 2, and engaged with the upper portions of the end rails are the hooks *d'* of the bows *d*. These bows *d* extend, 40 respectively, along the outer sides of the end bars *b* and have their outer edges bowed outward from the end bars, the greatest width of the bow being at the middle, as shown. The warp-threads are passed through the notches *c'* and *b'* of the parts *c* and *b* and are then carried under the frame, their ends being connected with the hammock-rings *e*, as indicated in the drawings, and said rings being drawn

together by a fastening, (not shown,) which may be of any suitable sort—for example, a 50 piece of string. The warp-threads, as shown in Fig. 1, form the warp of the hammock. The woof-threads are then woven in and out between the end bars *b* is filled, after which 55 the connection between the hammock-rings should be severed, and the structure of the hammock will be complete. The purpose of providing the bows *d* with their curved outer edges is to give the hammock its proper 60 concave form to prevent the doll or other object placed in the hammock from rolling out of the sides thereof. Were the warp-threads to be stretched merely over the end rails *b* and then passed under the frame and joined together the hammock when formed would 65 describe a plane surface; but the bows *d*, as shown, make it necessary to employ at the middle of the loom warp-threads of greater length than those at the sides, and when the rings of 70 the hammock are connected together as described all of the threads, notwithstanding that they may be of irregular length, are held taut with a uniform tension. From the foregoing it will be seen that the loom-frame is 75 flat and that the bows at the ends of the frame have their curved edges lying in a plane in or parallel to the plane of the loom-frame, whereby to hold the warp-threads in a flat plane in position for weaving.

Various changes in the form and details of my invention may be resorted to at will without departing from the spirit of my invention. Hence I consider myself entitled to all forms of the invention as may lie within the 85 intent of my claims.

Having thus described my invention, I claim as new and desire to secure by Letters Patent—

1. The combination with a loom-frame, comprising the side and end bars and the lay working on the side bars toward and from the end bars, of a bow extending along one of the end bars and having hooks engaged with the ends thereof, said bow having the warp-threads passed over its curved edge, for the purpose 95 specified.

2. The combination of a loom-frame, comprising side and end bars, of a bow extending along one of the end bars and having hooks engaged with the end thereof, said bow having 5 the warp-threads passing over its curved edge, for the purpose specified.

In testimony whereof I have signed my name

to this specification in the presence of two subscribing witnesses.

BEATRICE E. LINDBERG.
